(57) **CLAIM**

The ornamental design for a building construction board, as shown.

DESCRIPTION

FIG. 1 is a perspective view of a building construction board showing my design.

FIG. 2 is a top view thereof. The bottom view is a mirror image of this view and, therefore has been omitted.

FIG. 3 is an end view thereof; and,

FIG. 4 is a left side elevational view thereof. The right side elevational view is a mirror image of this view and therefore, has been omitted.
